UNITED STATES PATENT OFFICE.

THEODORE S. HIGLEY, OF ESCONDIDO, CALIFORNIA.

RAISIN-DRYING TRAY.

Application filed September 24, 1921. Serial No. 503,031.

My invention relates to a tray for drying raisins and the objects of my invention are: first, to provide a tray for drying raisins which may be placed on the ground so that the raisins may rest on the ground and so that drafts of air will not get at the raisins from below; second, to provide a tray of this class in which the supports are composed of wire so that moisture will not gather thereon; third, to provide a tray for drying raisins which is very efficient; fourth, to provide a novelly constructed raisin drying tray and fifth, to provide a tray of this class which is very durable.

With these and other objects in view as will appear hereinafter my invention consists of certain novel features of construction, combination and arrangement of parts and portions as will be hereinafter described in detail and particularly set forth in the appended claims, reference being had to the accompanying drawings and to the characters of reference thereon which form a part of this application in which:

Figure 1 is a top or plan view of my raisin drying tray in its preferred form; Fig. 2 is a fragmentary sectional view on an enlarged scale through 2—2 of Fig. 1; and Fig. 3 is an end view thereof.

Similar characters of reference refer to similar parts and portions throughout the several views of the drawings.

The side members 1, upper end members 2, lower end members 3 and wires 4 and 5 constitute the principal parts and portions of my raisin drying tray.

The side members 1 are preferably composed of wood or metal about three-quarters of an inch by one and one-half inches in cross section and the end members 2 are similar members about three-quarters of an inch by two inches in cross section and the corners are mortised so that the upper and lower edges of the frame formed by the members 1 and 2 are flush. Secured against the members 2 on the lower sides are the end members 3 which are approximately the same size as the members 2 and each of these members 3 is provided with a series of perforations therein in which the end of the wires 4 are inserted, the wires 4 being bent at a right angle at each end and inserted in the perforations so that when the members 3 are secured relatively to the members 2 the wires 4 are set and held securely in posi-

tion as shown best in Fig. 2. In order to further support the wires 4 there are provided a plurality of cross connecting wires 5 which are secured on the lower sides of the members 1 at their ends and interwoven with the cross wires 4 for holding the wires 4 in certain relation to each other and reinforcing the same between their ends. It is desired to space these wires 4 about three-eighths to one-half inch apart.

Though I have shown and described a particular construction, combination and arrangement of parts and portions I do not wish to be limited to this particular construction, combination and arrangement but desire to include in the scope of my invention the construction, combination and arrangement substantially as set forth in the appended claims.

It is obvious that with this construction there is provided a raisin drying tray in which the raisin supports are composed of fine wire so that moisture will not gather thereon; that the end members 3 may be imbedded in the ground and sand so that the wires will rest on the sand utilizing the heat of the earth as well as the sun for drying the raisins and that no air or draft will blow up under the same; the wires are galvanized so they will not rust and are not therefore subject to early decay.

Having thus described my invention what I claim as new and desire to secure by Letters Patent is:

1. A raisin drying tray, including a rectangular mortised flush frame, a plurality of wires secured on the lower side thereof, and end members secured over and engaging the ends of said wire at the ends only of said tray.

2. A raisin drying tray, including a rectangular mortised flush frame, a plurality of wires provided with right angled outwardly extending ends extending across the same, and separate cleats secured against the lower side of said frame at opposite ends only of said frame provided with depressions for receiving the right angled outwardly extending ends on said wires for supporting said wires.

In testimony whereof, I have hereunto set my hand at Escondido, California, this 17th day of September 1921.

THEODORE S. HIGLEY.
